CLAIM

The ornamental design for a buckling component applied to a magnetic buckling assembly, as shown and described.

DESCRIPTION

FIG. 1 is a top perspective view of a buckling component showing my new design;

FIG. 2 is a sectional view of the buckling component of FIG. 1 applied to a magnetic buckling assembly along the line A-A; and,

FIG. 3 is a bottom perspective view of the buckling component of FIG. 1 applied to a magnetic buckling assembly. The dash-dash broken lines shown in the drawings illustrate portions of the buckling component applied to a magnetic buckling assembly. The dot-dash broken lines shown in the drawings represent the claim boundary. The broken lines form no part of the claimed design.
